UNITED STATES PATENT OFFICE.

WILLIS S. FULLER, OF NEW BEDFORD, MASSACHUSETTS, ASSIGNOR TO MORSE TWIST DRILL & MACHINE COMPANY, OF NEW BEDFORD, MASSACHUSETTS, A CORPORATION OF MASSACHUSETTS.

REAMER.

1,172,589.

Specification of Letters Patent. Patented Feb. 22, 1916.

Application filed July 16, 1912. Serial No. 709,769.

To all whom it may concern:

Be it known that I, WILLIS S. FULLER, a citizen of the United States, residing at New Bedford, in the county of Bristol, State of Massachusetts, have invented a certain new and useful Improvement in Reamers, of which the following is a specification, reference being had therein to the accompanying drawings.

- 10 This invention relates to reamers, cutters, taps, and the like, but more particularly to such as are adjustable, and it has for its object to provide a more simple and efficient construction than has heretofore been known.
- 15 The same is particularly an improvement on the device disclosed in the United States patent of William J. Smith, numbered 783,904, and bearing date of February 28, 1905.
- 20 In the construction described in the patent above referred to, the stock was bored out to form a hollow tube in which was a central diaphragm dividing the tube into two compartments or chambers. The chamber in front of this diaphragm was adapted to contain a cutter controlling cam piece which was drawn longitudinally within the stock by a bolt co-acting with the diaphragm. To manufacture such a stock one chamber 25 was bored, the stock then inverted, and the other chamber bored. After inverting the stock, it was extremely difficult to so fix the same in the machine that the axis of the second chamber would exactly coincide with the axis of the first chamber. A slight inaccuracy in the boring of the chambers would cause the finished tool to operate inaccurately. To overcome this difficulty a construction has been devised in which the 30 entire boring of the stock may be done from one end of the same and no inverting or removing from the machine during the boring process is necessary.

The many features of the invention will 45 be fully described hereinafter and included in the claims.

Figure 1 is a longitudinal section of the invention complete. Fig. 2, same as Fig. 1, but with the cutter adjusting and locking 50 mechanism removed, as will be fully described hereinafter. Fig. 3, section on line 3—3 of Fig. 1, the cam piece being shown in full, as will be fully described herein- 55

after. Figs. 4 and 5, detail views, as will be fully described hereinafter. 60

Referring to the drawings, the preferred embodiment of the invention is shown to comprise a stock 10 bored out to form a hollow tube, as is best shown in Fig. 2 of the drawings. 65

The diameter of bore of the rear portion 11 of the tube is preferably greater than that of the forward portion 12 so that a shoulder 13 is formed at the junction of the two bores. The forward portion of the stock is 70 provided with slots 14 in which rest the cutters 15.

Within the forward chamber 12 of the stock rests the cam piece 16 which is provided with the cam faces 17 adapted to co-act with the under face of the cutters 15 so that when the cam piece is rotated within the chamber 12, the cutters are forced outwardly in the stock. 75

Extending rearwardly from the cam piece 16 is a bolt 18 upon which is the washer 19 preferably fitting the bore of the chamber 11 of the stock. This washer preferably forms a bearing for the rear end of the cam piece 16 and is adapted to act against 80 the shoulder 13 to permit the nut 20 upon the bolt 18 acting against the rear face of the washer to cause the cam piece 16 to be drawn rearwardly within the stock. 85

The cutters 15 are preferably firmly clamped to the cams in any position by means of the inclined face 21 of the cut away portion 22 in the cam piece acting against the corresponding inclined face of the tongue 23 projecting from the back edge of each 90 cutter as is best shown in Fig. 1.

In the forward extremity of the tube the diameter of bore is preferably reduced to form an annular flange 24 in which fits the reduced end 25 of the cam piece 16 and this flange forms a bearing for the forward end of the cam piece. In the earlier patent hereinbefore referred to, the extremities of the cam piece which formed the supporting surfaces therefor, were of greater radius 100 than the outer edges of the cam faces, so that it was extremely difficult to grind these cam faces without injuring the supporting surfaces. In the present invention these supporting surfaces are preferably of less 105 radius than the cam faces and thus do not

interfere with the grinding. The cam piece is preferably rotated by a key inserted in the slot 26 or by any other suitable means.

The applicant is aware that many changes in the construction and arrangement of parts may be made by anyone skilled in the art and he does not care to be limited to the particular embodiment herein shown and described except as required by the scope of 10 the claims.

What I claim as my invention and desire to secure by Letters Patent is:—

1. In a device of the class described, a stock bored to form a hollow tube, radially adjustable cutters in said stock, an annular shoulder formed on said stock and integral therewith in the bore of said tube near its forward extremity, and a rotary cam piece in said tube having its reduced forward extremity fitting within said annular shoulder as a bearing and its cam faces adapted to coact with said cutters.

2. In a device of the class described, a stock bored to form a hollow tube, radially adjustable cutters in said stock, an annular shoulder formed integral with said stock within said tube near its forward extremity, a rotary cam piece in said tube having its reduced forward extremity fitting within 25 said annular member as a bearing and its cam faces adapted to coact with said cutters, and a second annular member within said tube fitting the reduced rear end of said cam piece and forming a bearing therefor.

3. In a device of the class described, a stock bored to form a hollow tube, an an-

nular flange integral with said stock in the forward portion of said tube, radially adjustable cutters in said stock, a longitudinally adjustable rotary cam piece within 40 said tube having its reduced forward extremity fitting within said annular flange as a bearing and its cam faces adapted by rotation of the cam piece to adjust said cutters, means for clamping said cutters to said 45 cam faces by an endwise movement of the cam piece, and means for drawing the cam piece longitudinally in the stock.

4. In a device of the class described, a stock bored to form a hollow tube, an annular flange integral with said stock in the forward portion of said tube, radially adjustable cutters in said stock, a longitudinally adjustable rotary cam piece within 50 said tube having its reduced forward extremity fitting within said annular flange as a bearing and its cam faces adapted by rotation of the cam piece to adjust such cutters, means for clamping said cutters to said 55 cam faces by an endwise movement of the cam piece, means for drawing the cam piece longitudinally in the stock, and a second annular member within said tube fitting the reduced rear end of said cam piece and forming a bearing therefor.

In testimony whereof I affix my signature in the presence of two witnesses.

WILLIS S. FULLER.
